(57) CLAIM

The ornamental design for an X shaped dog toy, as shown and described.

DESCRIPTION

FIG. 1 is a top plan view of my new design for an X shaped dog toy.

FIG. 2 is a right side elevation view of FIG. 1.

FIG. 3 is a left side elevation view of FIG. 1.

FIG. 4 is a front elevation view of FIG. 1.

FIG. 5 is a bottom plan view of FIG. 1.

FIG. 6 is a rear elevation view of FIG. 1; and,

FIG. 7 is a top perspective view of Figure.

The evenly spaced broken lines represent stitching. The features shown in broken lines in the drawing depict environmental subject matter only and form no part of the claimed design.
